DRAFTING APPARATUS FOR TEXTILE FIBERS

Joseph Noguera, Salford, England, assignor to
 Casablanca High Draft Company Limited,
 Lancaster, England, a British company

Application January 23, 1950, Serial No. 139,999

Claims priority, application Great Britain
 February 2, 1949

13 Claims. (Cl. 19—131)

1

This invention relates to drafting apparatus for textile fibres of the kind in which the fibres are caused to pass between and are controlled by adjacent runs of two endless belts or bands, arranged to form elongated loops and superposed one above the other, the loops being supported at their rear ends by rollers which interact to form a positive nip between the said adjacent runs and which are arranged to drive the loops in the direction of feed of the fibres, and the loops being supported at their forward or front ends by means of a tensor carried by a cradle, the tensor being arranged to form a delivery nip between the runs which is located very close to a further positive nip formed between a following pair of drafting rollers. The term "positive" nip as used herein means a nip which exerts a substantially non-yielding grip on the fibres as opposed to the soft yielding grip of the delivery nip between the endless belts. The foregoing arrangement is in accordance with the standard two-belt apparatus used in the well known Casablanca Drafting System.

With this apparatus however, the maximum length of the fibre-controlling belt runs must, of necessity, be limited owing mainly to the fact that the said runs are, in effect, propelled forward towards the tensor from the rear by the driving rollers and therefore, if the belt runs are too long, they will tend to deform and cease to exercise proper fibre control. The length of these belt runs depends upon the distance apart of the two positive nips as aforesaid which are formed respectively between the belt-supporting rollers and the succeeding drawing rollers, the positive nip between the succeeding drawing rollers having in any case to be close to the delivery nip of the belts because, if this distance greatly exceeds the length of the shortest fibres being drawn, the control exercised on these fibres again will not be satisfactory. As will be realised however, in order to obtain the advantages of the endless belt system of drafting, the two positive nips immediately preceding and immediately succeeding the delivery nip must be at a distance apart at least a little greater than the length of the longest fibres being drawn since otherwise such fibres will be positively gripped at each end during the drawing operation and the soft yielding delivery control exercised by the belts will be largely ineffective as far as the fibres so gripped are concerned. It should be pointed out that one way of reducing the risk of the fibre-controlling belt runs undulating or becoming unsteady when they are longer than normal is to mount them relatively taut. This, however,

2

is unsatisfactory from the point of view of drafting efficiency because the action of the two belts upon the fibre becomes proportionately harsher the tighter the belts are, the degree of fibre retention exercised by the tight belts, furthermore, varying easily from too much to too little.

For the foregoing reasons, the length of the fibre-controlling belt runs which has been adopted in the standard Casablanca apparatus is such that the distance between the positive nip formed by the belt-supporting rollers and the positive nip formed by the succeeding drawing rollers is only some $1\frac{1}{8}$ ". This permits the very satisfactory drafting of fibres such as cotton, with lengths ranging up to a maximum of about $1\frac{1}{4}$ ".

A main object of the present invention is to provide a generally improved drafting apparatus of the kind specified which is capable of dealing satisfactorily with a much wider range of fibre lengths than has been possible heretofore in any one apparatus.

According to the present invention, in a drafting apparatus of the kind specified, there is provided means, including at least one platform member, for supporting the fibre-controlling belt runs and for determining the distance apart of the positive nips which respectively immediately precede and immediately succeed the delivery nip, said means being carried on the cradle and being arranged to act on the inner surface of the lower fibre-controlling belt run to provide said support and to determine said distance. This arrangement permits the use of belts, the fibre-controlling runs of which are considerably longer than those normally used whilst the distance apart of the positive nips immediately preceding and immediately succeeding the delivery nip of the belts can be varied according to the maximum length of the fibres being drawn.

In order that the invention may be clearly understood and readily carried into effect several embodiments thereof will now be described in detail with reference to the accompanying drawings wherein:

Figure 1 is a part-sectional side elevation illustrating the relevant portions of a drafting apparatus and showing one embodiment of the means according to the invention in the operative position.

Figure 2 is a sectional side elevation of the means shown in Figure 1, parts of the co-operating belts being inserted in chain-dotted lines.

Figure 3 is a front elevation according to Figure 2,

Figures 4 and 5, 6 and 7, and 8 and 9, are views

respectively similar to Figures 2 and 3 but each showing differently shaped means whereby the distance apart of positive nips can be varied,

Figure 10 is a view similar to Figure 1 illustrating an alternative embodiment of the means according to the invention,

Figure 11 is a plan view of the cradle and means shown in Figure 10,

Figure 12 is a section on the line XII—XII of Figure 10, the belts and driving rollers being omitted,

Figure 13 is a view similar to Figure 1 but showing yet another alternative embodiment of the means according to the invention,

Figure 14 is a section on the line XIV—XIV of Figure 13, the belts and driving rollers being omitted, and

Figure 15 is a detail perspective view of the means shown in Figures 13 and 14.

Referring now to the drawings, and more particularly to Figures 1 to 9, a pair of co-operating elongated endless belts 1, 2 are mounted at their rear ends on co-operating driving rollers 3 and are held in the correct working position at their forward ends by means of a two-pronged tensor 4, the belts forming a delivery nip between the prongs of this tensor. The tensor 4 is carried on a cradle consisting mainly of a pair of parallel side walls 5 which extend one along each side of the belts 1, 2 and each of which is shaped at the rear end as shown to engage the spindles of the driving rollers 3. Approximately centrally, and towards their lower edges, the side walls 5 are joined by a cross-member 6. At the entry end of the adjacent runs of the belts 1 and 2 between which the fibres pass there is arranged, in known manner, a condenser 7 mounted on a traverse bar 8, and at the opposite or delivery end of these runs there is arranged, again in known manner, a pair of following drawing rollers 9 which form a positive nip therebetween. The arrangement of the driving rollers 3 is such that a positive nip is also created thereby between the belt runs at the entry end of the latter.

In this example, the centre distance between the belt-supporting rollers 3 and the following drawing rollers 9 is some $3\frac{1}{2}$ " which is considerably larger than normal, the overall length of the cradle and the length of the fibre-supporting belt runs being correspondingly increased. An elongated slot 10 is formed in each side wall 5 of the cradle, the slots opening into the upper edges of these side walls and being positioned opposite to one another. The dimensions of the slots are such that upstanding side lugs 11, formed one at each end of a downturned flange 11a provided along the leading edge of a platform member 12, can be entered therein so that the said platform member 12 is supported between the side walls 5 of the cradle immediately below the fibre-controlling run of the lower belt 2 as shown. To withdraw the platform member 12 from the cradle it is necessary merely to raise the platform relatively to the side walls 5 until the lugs 11 are clear of the slots 10.

A plurality of such platforms 12, 12a, 12b and 12c are preferably provided as shown in Figures 2 to 9, each being of different shape depending upon the fibre lengths with which it is to be used. Each of the platforms is provided with a flange 11a and upstanding side lugs 11. As can be seen from Figures 1 and 2, platform 12 is shaped to extend substantially parallel to the belt runs when in position and serves as an intermediate support for these runs to prevent defor-

mation thereof and to ensure proper fibre control. When the platform 12 is in use, the distance apart of the positive nips which immediately precede and immediately succeed the aforesaid delivery nip is substantially equal to the centre distance between the belt-supporting rollers 3 and the succeeding drawing rollers 9, in this case some $3\frac{1}{2}$ " as aforesaid. The other platform members 12a, 12b and 12c are respectively bent along lines 13, 13a and 13b which are each parallel to the flange 11a of the platform. The distance between the line of bend and the flange 11a is different for each platform and so arranged that, when any one of the bent platform members 12a, 12b or 12c is in position in the cradle, the fibre-controlling belt runs are both supported and sharply deflected in the upward direction along the line of bend of the platform. An intermediate positive nip is thus introduced into the length of the co-operating belt runs which immediately precedes the delivery nip and is closer thereto, and therefore also to the succeeding positive nip, than is the nip formed between the driving rollers 3. A different number of notches 14 are provided in the flange 11a of each platform so that the various platforms can easily be differentiated one from the other and can therefore be quickly selected and inserted as required.

In the particular apparatus described in the foregoing, fibres up to 3" in length can be drafted successfully merely by interchanging the platform members as required, the supporting platform shown in Figures 1, 2 and 3 being utilized when the longest fibres are being drafted so that the distance between positive nips immediately preceding and immediately succeeding the delivery nip is a maximum, and any one of the supporting and deflecting platforms shown in Figures 4 to 9 being utilized to bring the positive nip which immediately precedes the delivery nip closer to the said delivery nip and the succeeding positive nip when it is desired to draft the shorter fibres. The actual distance between the nips immediately preceding and immediately succeeding the delivery nip, will, of course, depend upon the particular deflecting platform used so that this distance can be varied to provide optimum drafting conditions for various fibre lengths.

In the modified arrangement shown in Figures 10 to 12 the interchangeable platforms are replaced by a fixed platform 15 having downturned ends 15a formed with side projections 15b which are entered through slots formed to receive them in the cradle walls 5 and have their projecting ends burred over in the manner of rivets. In this arrangement therefore the cross-bar 6 is omitted since the cradle walls are held together by the aforesaid platform 15. Two spaced substantially triangular apertures 16 are provided in each cradle wall 5 so that the base of each aperture is substantially level with the top of the platform 15, and substantially triangular notches 17 are provided in the platform top opposite each of the aforesaid apertures 16. A transverse member 18, of substantially triangular cross-section, with one tapered end 18a and a handle 18b at the other end, is provided for insertion, when desired, through a pair of opposite apertures 16 in the side walls 5 of the cradle as shown in Figures 11 and 12, the base of the member 18 being arranged to bear on the platform top and the upper edge of the member being arranged to bear against the under-surface

of the lower fibre-controlling belt run. The provision of the notches 17 facilitates the initial entry of the tapered end 18a of member 18 between the aforesaid platform and belt run.

In use, during the drafting of the longest fibres, the fixed platform 15 provides a support for the belt runs and the distance apart of the positive nips immediately preceding and immediately succeeding the delivery nip corresponds with the centre distance between the roller pairs 3 and 9. When it is desired to draft shorter fibres, the member 18 can be inserted on top of the platform through either pair of apertures 16 and under the lower belt run to bring the positive nip immediately preceding the delivery nip closer to the latter as required.

In the third embodiment shown in Figures 13 to 15, the cradle walls 5 are secured together by two transverse Z-section members 19 and a platform 20 is provided having a dependent lug 21 on each side. The lugs 21 are each provided with a small outwardly extending projection 22 and these projections 22 are arranged to engage respectively in apertures 22a formed to receive them in the cradle walls 5. The projections 22 thus form pivots for the platform 20. An L-shaped outwardly extending arm member 23 is provided on the lower end of each lug 21 and each arm member 23 is arranged to project through an aperture 24 in the adjacent cradle wall 5. The parts of the arms 23 which extend through the apertures 24 are formed partially with a narrow or neck portion 23a and partially with a wider portion 23b. The slots 24 are each provided along the upper and lower edges with notches as at 25 and the widened portion 23b of each arm is normally engaged in one of these notches in the appropriate slot. The platform is made of sufficiently thin material to allow a certain amount of spring action and, in order to effect adjustment, the arms 23 are pressed towards each other until the narrowed portions 23a are located within the slots 24. In this position the arms can be moved along the slots in either direction to tilt the platform one way or the other as shown in chain-dotted lines in Figure 13. When the pressure on the arms 23 is released the lugs 21 spring outwards again and the portions 23b of the arms re-engage in the nearest notches 25 and thereby hold the platform in the adjusted position. The position of the platform will, of course, be varied according to the required distance apart of the positive nips immediately preceding and immediately succeeding the delivery nip as explained in connection with the first two embodiments. The opposite narrow edge portions of the platform 20 comprises the means for imparting the positive nip to the belts when either of these edge portions is brought into the extreme positions shown in Figure 13 of the drawings.

I claim:

1. In a drafting apparatus for textile fibres, the combination of a pair of superposed endless belts in elongated loop form and having adjacent operative runs for controlling fibres caused to pass therebetween, a pair of driving rollers each supporting one belt loop at the rear end of the latter and forming a substantially non-yielding positive inlet nip between the rear ends of said operative belt runs, tensor means supporting the forward ends of said belt loops and forming a yielding delivery nip between the leading ends of said operative belt runs, two parallel wall mem-

bers arranged one on each side of said belt loops for laterally guiding the latter and a transverse platform member which rigidly couples said side wall members together and constituting the sole coupling means between said wall members, said platform member being located in its entirety between the runs of the lower belt loop and having a plane upper surface capable of supporting the said operative belt runs and spaced from said tensor means.

2. The combination as claimed in claim 1 further including a removable transverse member shaped for positioning between said platform member and the under-surface of the lower fibre-controlling belt run so as to deflect said fibre-controlling runs and thereby introduce a positive nip which immediately precedes said delivery nip and is closer to the said delivery nip than is said positive nip between the said driving rollers.

3. Drafting means for use in a drafting apparatus for textile fibres, said means comprising a pair of superposed endless belts in elongated loop form and having co-operating fibre-controlling runs, a pair of feeding rollers each supporting one loop at the rear end of the latter and forming a positive inlet nip between the rear ends of said fibre-controlling belt runs, tensor means supporting the forward ends of said belt loops and forming a yielding delivery nip between the leading ends of said fibre-controlling belt runs, a pair of co-operating front drawing rollers arranged close to said delivery nip and forming a positive nip therebetween, two parallel side wall members arranged one on each side of said belt loops to provide a cradle for laterally guiding the latter, said wall members each being shaped at the rear end partially to embrace the spindle of each said feeding roller, and a transverse platform member which rigidly couples said side wall members together and constitutes the sole coupling means between said wall members, said platform member being located between the runs of the lower belt loop and having a flat upper surface which is arranged to support the said fibre-controlling belt runs without substantially deflecting the latter.

4. In a drafting apparatus for textile fibres, the combination of a pair of superposed endless belts in elongated loop form and having adjacent operative runs for controlling fibres caused to pass therebetween, a pair of driving rollers each supporting one belt loop at the rear end of the latter and forming a substantially non-yielding positive inlet nip between the rear ends of said operative belt runs, tensor means supporting the forward ends of said belt loops and forming a yielding delivery nip between the leading ends of said operative belt runs, two parallel wall members arranged one on each side of said belt loops for laterally guiding the latter and a continuous platform extending transversely of said belts from one wall member to the other wall member which rigidly couples the wall members together and constituting the sole coupling means between said wall members, said platform member being separate from said tensor means and being disposed intermediate said driving rollers and said tensor means and being disposed in its entirety between the runs of the lower belt loop and having a plane upper surface capable of supporting the entire width of the operative runs of the belts throughout the length of the platform member.

5. In a drafting apparatus for textile fibres, the combination of a pair of superposed endless

belts in elongated loop form and having adjacent said driving rollers providing a positive nip and at the opposite end by tensor means providing a delivery nip, a guiding device comprising two parallel spaced walls adapted to engage opposite edges of the belts, a supporting member extending between and supported by said walls and having a surface adapted to support the upper run of the lower belt of said belts, said walls having at least two substantially triangular shaped apertures the bases of which are substantially flush with the surface of the supporting member, the apertures of one wall being in alignment with the corresponding apertures in the other wall, and a substantially triangularly shaped element for selective insertion through a pair of aligned apertures with its base resting upon the surface of the supporting member and its apex exerting pressure against the adjacent runs of the belts intermediate the positive and delivery nips to impart a positive nip thereto.

6. For use with a drafting mechanism having a pair of superposed endless belts in elongated loop form supported at one end by a pair of driving rollers providing a positive nip and at the opposite end by tensor means providing a delivery nip, a guiding device comprising two parallel spaced walls adapted to laterally guide the belts, and a supporting member fixed to said walls adapted to engage and support the upper run of the lower of the endless belts intermediate the positive nip and the delivery nip, said supporting member fixedly coupling said walls together and constituting the sole coupling means between said walls.

7. For use with a drafting mechanism having a pair of superposed endless belts in elongated loop form supported at one end by a pair of driving rollers providing a positive nip and at the opposite end by tensor means providing a delivery nip, a guiding device comprising two parallel spaced walls adapted to engage opposite edges of the belts, and a supporting member fixed to said walls and having a flat surface adapted to engage and support the upper run of the lower of the endless belts intermediate the positive nip and the delivery nip to impart a yielding nip to the belts, a transverse member adapted to be positioned between said supporting member and the upper run of the lower belt and supported by said supporting member and having a surface adapted to engage the upper run of the lower belt and so shaped as to exert a pressure on the belt runs intermediate the positive and delivery nips to form a positive nip therein.

8. For use with a drafting mechanism having a pair of superposed endless belts in elongated loop form supported at one end by a pair of driv-

ing rollers each supporting one belt loop at the rear end of the loop and providing a first positive nip, and tensor means supporting the forward ends of the loops and providing a delivery nip, a guiding device comprising two parallel spaced apart walls adapted to laterally guide the belts, and supporting means extending from one wall to the other and having opposite end portions attached to said walls and adapted selectively to impart a second positive nip or a non-positive nip to the belts, said supporting means when imparting a non-positive nip to the belts having supporting engagement with the upper run of the lower belt throughout a substantial longitudinal area thereof and when imparting a positive nip to the belts having a supporting engagement with the upper run of the lower belt along a short longitudinal area thereof.

10. A guiding device as claimed in claim 9, wherein said supporting means comprises a platform having a transversely bent portion adapted to engage the upper run of the lower of the belts intermediate the delivery nip and the first positive nip for deflecting the adjacent runs of the belts to form second positive nip therein.

11. For use in a drafting apparatus for textile fibres of the kind including a pair of superposed endless belts in elongated loop form and having cooperating fibre-controlling runs, a pair of driving rollers each supporting one loop at the rear end of the latter and a two-pronged tensor supporting the forward ends of said belt loops, the combination of two side wall members adapted to laterally guide said belt runs and support said tensor, said side wall members each being shaped at the rear end to partially embrace the spindles of said driving rollers, a platform member which rigidly couples said side walls together and has a plane upper surface, said platform member adapted to be located in its entirety between the runs of the lower belt and constituting the sole coupling means between said wall members so as to support said fibre-controlling belt runs when said side walls are in position on the apparatus, and a transverse member adapted to be optionally arranged to rest on the said upper surface of said platform member to deflect said fibre-controlling belt runs and form a positive nip therewith.

12. A guiding device as claimed in claim 9, wherein said supporting means comprises a set of platforms for selective use one of which has a substantially flat surface for engaging the upper

run of the lower belt to impart the non-positive nip to the belts and each of the other platforms having a transversely extending bent portion at a location different from that of each of the said other platforms to impart the second positive nip at different locations longitudinally of the belts.

13. A guiding device as claimed in claim 9 wherein said supporting means comprises a platform having an elongated flat surface provided with narrow edge portions, said platform being pivotally mounted on said walls, and means on said walls and platform for detachably holding said platform in various positions, whereby said platform surface and edge portions are caused to selectively engage the upper run of the lower belt 15

for selectively forming the second positive nip or the non-positive nip of the belts between the delivery nip and the first positive nip.
